UNITED STATES PATENT OFFICE.

WILLIAM GADD, OF MANCHESTER, ENGLAND.

GAS-HOLDER.

No. 833,315.

Specification of Letters Patent.

Patented Oct. 16, 1906.

Application filed January 19, 1906. Serial No. 296,861.

To all whom it may concern:

Be it known that I, WILLIAM GADD, a subject of the King of Great Britain, residing at 64 Barton Arcade, Manchester, in the county 5 of Lancaster, England, have invented new and useful Improvements in Columnless Gas-Holders Supported by Helical Guides, (for which I have made application for patent in Great Britain with provisional specification 10 No. 24,899, bearing date of December 1, 1905,) of which the following is a specification.

The improvements relate to columnless gas-holders which are supported during their ascent and descent by means of helical guides; 15 and the object of the invention is to give to gas-holders of this description, in manner hereinafter to be described, a vertical rise and fall in lieu of the screw-like or helical motion obtained with ordinary helically-guided 20 gas-holders. Furthermore, the present invention forms a modification in construction of an invention for controlling gas-holders which is the subject of an application for patent in the United States previously filed 25 by me under the same title as the present. To accomplish this and to effect my improvements, I mount the helical guides on the vertical sides of the tank in the case of single-lift gas-holders, or on the inside of the 30 lower lift in multiple-lift gas-holders, in a manner similar to what has heretofore, to some extent, been arranged, and, in addition, vertical guides are employed, as many as may be found requisite, to prevent the turning 35 movement due to the friction of the helical guides. The present vertical stays may be utilized to form the vertical guides aforesaid when desirable. The guide-rollers into 40 which the helical guides take instead of being arranged as fixtures or resistance-points, as in ordinary helically-guided holders, are attached to a ring or band of suitable formation capable of moving horizontally around the circle in such manner that as the holder 45 rises and falls vertically the helical guides give a horizontal circular motion to such ring instead of a helical motion to the holder itself. Nevertheless this ring, traveling horizontally in suitable bearings or supports, 50 firmly and securely grips or holds the holder at all heights and yet enables the holder to rise and fall vertically, thus obviating any inconvenience which in some cases may possibly ensue from the screw-like or helical rise 5 and fall which is characteristic of the ordinary helically-guided gas-holder; but that the

improvements may be better understood I will, with the aid of the accompanying drawings, proceed to more fully describe means employed by me.

Figure 1 is a view in elevation, part thereof being shown in section, of a portion of a gas-holder; and Fig. 2 is a sectional elevation of portions of the gas-holder and tank-wall, while Fig. 3 is a plan, on a smaller scale, of the said portions of a gas-holder and tank-wall, all arranged according to my invention. Figs. 4 and 5 show sectional elevations illustrating adaptations of the invention to the inner and outer lifts of telescopic gas-holders.

a represents the wall of the gas-holder tank, which tank, as is well known, forms what may be termed a "socket" for the reception of the gas-holder. The tank-wall is omitted from Fig. 1 for the sake of clearness, and *c* represents guide-rails mounted thereon in helical form, while *k* represents vertical guides, also attached to such tank-wall.

b is the gas-holder bell, and *d* represents the rollers for engaging with the rails *c*, which rollers in ordinary helically-guided gas-holders are arranged as fixtures or resistance-points, but which in accordance with my present improvements are attached to a ring or band *e*, capable of moving horizontally around the circle. Antifriction-rollers *h* are shown provided upon the gas-holder *b* for supporting the ring or band *e* and for allowing the same to freely move in a circular path when necessary. These rollers *h* are in Fig. 2 attached to the gas-holder near the bottom thereof, in Fig. 4 they are mounted upon the side of the cup of an upper lift, and in Fig. 5 they are mounted beneath such cup, the rollers in the latter case projecting within a ring *e*, of channel section, which is here employed in lieu of the flat band *e* of Figs. 1 to 4.

The rollers *d* upon the ring or band *e* engage with the helical rails *c*, and thus enable the holder to be securely gripped or held at all heights of its rise and fall.

The vertical guides *k*, in number as may be found requisite, take into guide-rollers, such as *l*, mounted on the gas-holder (on the upper lift in Figs. 4 and 5) for the purpose of preventing the turning movement of the holder, due to the friction of the helical rail *c*, and to cause such holder to take a vertical rise and fall.

In Figs. 4 and 5 the vertical guides *k* and helical rails *c* are shown attached to the in-

side of the outer lift of the gas-holder, which outer lift may in its turn be described as a "socket" for the reception of the remainder of the gas-holder, while the rollers *l* and *h* are, as described in connection with the cupping or dip portion of the inner lift of the gas-holder, for telescoping purposes.

In operation it will be seen that as the gas-holder rises or falls it is prevented from turning by reason of the vertical guides *k* engaging with the fixed rollers *l*, but that the inclination of the helical guides *c*, taking into the rollers *d*, will while the holder is in motion impart a circular movement to the band or ring *e*, by which means the holder will be firmly held at all working heights, any tilting of the holder being prevented by reason of the ring *e* enabling all lateral pressures to be resisted at the gripping-points around the circle.

Having now particularly described and ascertained the nature of my said invention and in what manner the same is to be performed, I declare that what I claim is—

In gas-holders supported by helical guides, a ring free to move horizontally about a periphery of the gas-holder, antifriction-rollers supporting and guiding said ring and mounted on the gas-holder, guide-rollers mounted on said ring, helical rails taking into said guide-rollers and mounted on the socket within which the gas-holder carrying the ring rises and falls, vertical rails mounted on said socket, and guide-rollers taking into said vertical rails and mounted on the gas-holder, substantially as set forth.

WILLIAM GADD.
